UNITED STATES PATENT OFFICE.

JULIAN B. LA PIERRE, OF CHICAGO, ILLINOIS.

DESIGN FOR A GEAR-SHIFT-LEVER KNOB.

Application filed April 12, 1928. Serial No. 26,297. Term of patent 7 years.

To all whom it may concern:

Be it known that I, JULIAN B. LA PIERRE, a citizen of the United States, residing at Chicago, in the county of Cook and State of Illinois, have invented a new, original, and ornamental Design for Gear-Shift-Lever Knobs, of which the following is a specification, reference being had to the accompanying drawing, forming part thereof.

Figure 1 is a top plan view of a gear shift lever knob showing my new design.

Figs. 2 and 3 are side elevations of the same.

I claim:

The ornamental design for a gear shift lever knob as shown.

JULIAN B. LA PIERRE.
